(57) **CLAIM**

The ornamental design for an ice skate shaped carabiner, as
shown and described.

DESCRIPTION

FIG. 1 is a top or bottom plan view of my new design for an
ice skate shaped carabiner.

FIG. 2 is a bottom plan view of an alternate embodiment of
FIG. 1, the only difference being the bottom surface, it being
understood that all other surfaces are the same as those of the
first embodiment.

FIG. 3 is a left side elevation view of FIG. 1.

FIG. 4 is a right side elevation view of FIG. 1.

FIG. 5 is a front side elevation view of FIG. 1.

FIG. 6 is rear side elevation view of FIG. 1; and,

FIG. 7 is a top perspective view of FIG. 1.
